UNITED STATES PATENT OFFICE.

EDGAR A. EDWARDS, OF CINCINNATI, OHIO, ASSIGNOR TO EDWARDS RAIL-ROAD ELECTRIC LIGHT COMPANY, A CORPORATION OF INDIANA.

SIGNAL-LIGHT.

SPECIFICATION forming part of Letters Patent No. 738,781, dated September 15, 1903.

Application filed November 30, 1901. Serial No. 84,277. (No model.)

To all whom it may concern:

Be it known that I, EDGAR A. EDWARDS, a citizen of the United States, residing at Cincinnati, in the county of Hamilton and State of Ohio, have invented certain new and useful Improvements in Signal-Lights, of which the following is a specification.

My invention relates to locomotive-head-lights, and especially to those headlights which are provided with reflectors for the purpose of projecting a portion of the rays upward for signaling purposes; and my invention consists in the construction and arrangement of the reflector, as fully set forth hereinafter and as illustrated in the accompanying drawings, in which—

Figure 1 is a sectional elevation of sufficient of a locomotive-headlight to illustrate my improvement. Fig. 2 is a plan view.

The general features of my invention correspond to those of the Letters Patent to Samuel H. Harrington, No. 495,938, dated April 18, 1893, where there is a supplemental reflector arranged in front of the headlight-casing to project a portion of the light-rays upward.

The casing A of the headlight, the reflector C, and the lamp B are of any of the usual constructions, the rays of the lamp being thrown forward by the reflector through the ordinary goggle-plate D.

For the purpose of signaling and to throw a portion of the light-rays upward I make use of a supplemental reflector E, which, however, instead of consisting of an opaque plate with a reflecting-surface, as heretofore, consists of a plate of plain glass, which may be arranged so as to receive all of the light-rays

passing from the reflector C, as indicated in full lines, Fig. 1. The rays of light passing to the plate E are partly reflected upward and partly pass through the said plate, so that there is secured both the horizontal and the vertical rays required in such cases. The reflector E may be stationary; but, as shown, it is placed in a frame connected with a shaft 1, having an arm 2, connected by a rod 3 with any reciprocating portion of the engine—as, for instance, the valve-shaft—so that an oscillating or vibrating motion is imparted to the reflector-plate, thereby indicating whether the engine is in motion.

Without limiting myself to the specific construction and arrangement of parts shown, I claim as my invention—

1. The combination with a locomotive-head-light, of a signal-reflector consisting of a transparent plate arranged to receive all the horizontal rays and to transmit a part of the said rays horizontally and to reflect a part at an angle to the horizontal rays.

2. The combination with the casing, reflector and lamp of a locomotive-head-light, of a transparent plate arranged in front of the casing at an angle thereto to permit a portion of the horizontal light-rays to pass horizontally and also to reflect a portion upward, and means for vibrating said plate, substantially as set forth.

In testimony whereof I have signed my name to this specification in the presence of two subscribing witnesses.

EDGAR A. EDWARDS.
